UNITED STATES PATENT OFFICE.

ALFRED C. MINER, OF MISSOULA, MONTANA.

TROLLEY-HARP FASTENER.

1,164,955.

Specification of Letters Patent. Patented Dec. 21, 1915.

Application filed August 4, 1915. Serial No. 43,626.

To all whom it may concern:

Be it known that I, ALFRED C. MINER, a citizen of the United States, residing at Missoula, in the county of Missoula and State of Montana, have invented a new and useful Trolley-Harp Fastener, of which the following is a specification.

The device forming the subject matter of this application is a trolley pole, and the invention aims to provide a pole so constructed that the constituent parts of the pole may have relative movement in a vertical plane parallel to the direction of advance of the pole, and have, also, a lateral movement in a plane at right angles to the direction in which the pole is advancing, the ends in view being, in the one instance, to maintain the trolley wheel engaged with the conducting wire and, upon the other hand, to permit a lateral movement of the upper portion of the trolley pole when the car of which the trolley pole constitutes a part is rounding a curve.

Another object of the invention is to provide a novel mechanism whereby the constituent parts of the trolley pole are permitted to have relative movements in two rectangularly disposed planes, as distinguished from a construction in which the upper portion of the trolley pole is allowed a rocking movement, and a rotary movement on an axis.

Another object of the invention is to provide, in a device of the class described, a spring or sleeve which at once permits the necessary movement between the sections of the trolley pole, serves to hold the upper section of the trolley pole sustained, so that the trolley wheel will engage with the conductor, and shields the link which forms an operative connection between the trolley pole sections.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—Figure 1 shows the invention in side elevation; Figs. 2 and 3 are elevations, wherein the trolley pole is viewed at right angles in the respective views, the sleeve being broken away and parts appearing in section.

In carrying out the present invention there is provided a pole comprising a lower section 1 enlarged as shown at 2 to define a shoulder 3 receiving an abutment 4, preferably in the form of a ring, the abutment 4 being held in place by a rivet 5 or other securing device.

The upper section of the trolley pole is denoted by the numeral 6 and carries a harp 7 in which is journaled a trolley wheel 8. Adjacent its lower end, the upper section 6 is enlarged as shown at 9 to form a shoulder 10 receiving an abutment ring 11 held in place by a rivet 12 or otherwise.

The enlarged end 2 of the lower section 1 is provided with ears 14, and on the enlarged end 9 of the upper section 6 there are ears 15, the ears 14 and 15 standing at right angles to each other.

The invention contemplates the use of an intermediate link 16 having a reduced, thinned end 17, and a reduced, thinned end 18. The end 17 of the link is received between the ears 14 of the lower section 1, the end 18 being received between the ears 15 of the upper section 6. A pivot element 19 passes through the end 17 and through the ears 14, a pivot element 20 passing through the end 18 and the ears 15.

Surrounding the enlarged ends 2 and 9 of the pole sections and embracing the same closely is a resilient sleeve in the form of a tightly wound helical spring 21, one end of which engages with the abutment 4, the other end of which coacts with the abutment 11.

The construction is such that the upper section 6 of the pole may swing vertically in a plane parallel to the line of advance of the pole, and may swing laterally in a direction at right angles to the line of advance of the pole, without having a universal or wobbling movement, such a movement tending to cause the trolley wheel 8 to jump from the overhead conductor 25 wherewith the wheel coacts. The spring 21 serves to uphold the upper section 6 of the trolley pole with sufficient force so that a contact adequate to prevent arcing at the point of contact between the wheel 8 and the overhead

conductor will be secured. The link 16 together with its pivot elements forms an efficient conductor, in connection with the sections 1 and 6. The spring 21 not only 5 exercises its obvious function as a means for holding the sections 1 and 6 in approximate axial alinement, but, as well, constitutes a housing within the contour of which is located the link 16 and its pivot elements 10 19 and 20. The ends of the spring 21 engage the abutments 4 and 11 when the pole is flexed, and thus a proper contact is at all times secured at the points where the pivot elements 19 and 20 pass through the link 16. 15 The spring 21, it is to be observed, is connected with the pole sections 1 and 6, independently of the harp 7, and consequently, the harp and the wheel 8 may be renewed or changed without tearing down the flexible 20 pole joint constituting the subject matter of this application.

Having thus described the invention, what is claimed is:—

1. In a device of the class described, a pole comprising upper and lower sections; a link interposed between the sections and pivoted thereto, the link and the sections being pro-

vided with interengaging elements whereby the upper section will be held to the lower section for movement in two relatively fixed 30 rectangularly disposed planes; and a resilient sleeve surrounding the ends of the sections and housing the link.

2. In a device of the class described, a pole comprising upper and lower sections; a link interposed between the sections and pivoted thereto, the link and the sections being provided with interengaging elements whereby the upper section will be held to the lower section for movement in two relatively fixed 35 rectangularly disposed planes; an abutment on the upper section; an abutment on the lower section; and a helical spring interposed between the abutments, the helical spring receiving the adjacent ends of the sections and constituting a housing for the link.

In testimony that I claim the foregoing as my own, I have hereto affixed my signature in the presence of two witnesses.

ALFRED C. MINER.
